(57) **CLAIM**

The ornamental design for a tool handle, as shown and described.

DESCRIPTION

FIG. 1 is a perspective view of the tool handle according to the present design;

FIG. 2 is a left side elevation view of the tool handle as shown in FIG. 1, the right side elevation view being a mirror image thereof;

FIG. 3 is a top plan view of the tool handle as shown in FIG. 1, the bottom plan view being a mirror image thereof;

FIG. 4 is a front view of the tool handle as shown in FIG. 1;

FIG. 5 is a rear view of the tool handle as shown in FIG. 1;

FIG. 6 is a top plan view of the tool handle as shown in FIG. 1, showing a protective cap removed from the base; and,

FIG. 7 is a top plan view of the tool handle as shown in FIG. 6, with a protective cap secured to the front of the tool handle.

The features shown in broken lines in FIGS. 1, 2, 3, 4, 5 and 6 depict portions of the tool handle that form no part of the claimed design.

1 Claim, 5 Drawing Sheets
